UNITED STATES PATENT OFFICE.

PAUL H. W. WENDT, OF JERSEY CITY, NEW JERSEY.

CLOTHESPIN.

Application filed March 17, 1927. Serial No. 175,993.

My invention relates to clothes-pins, and its object is to provide at very low cost a strong and durable article for suspending garments or other articles to be dried from a clothes-line in such manner that they will be gripped so that there will be no danger of injury to the garments, or liability of their becoming accidentally separated from the pins, or the pins becoming detached from the lines even in most violent winds.

My improved clothes-pin comprises two members, each made of one piece of material, preferably non-corrosive wire, bent to peculiar shape, one member being pivotally connected at one end to the other member, allowing a swinging motion, so that it may be moved into a position to pass over a portion of the other member with a bight which yields and clamps a garment or other article of linen or textile fabric securely between the two members.

The device is equally well adapted for use either on a stationary clothes-line or a pulley line.

The details of construction and operation are hereinafter particularly described.

In the accompanying drawing:

Figure 1 is a side elevation of my improved clothespin when not in use.

Fig. 2 is a side elevation of the same showing it attached to a clothes-line of the pulley type, with a fabric clamped between the two members, the clothes-line and fabric being in cross section.

Fig. 3 is a rear view of the same, and

Fig. 4 is a detached rear view of the clamping member, showing a modified form of securing its ends.

Referring to the drawing, the body member A of the clothes-pin consists of a single length of material, preferably non-corrosive wire, bent over at 10, to form two opposite jaws 11 and 12, which slightly diverge so that the space between them is somewhat greater at the lower part than at the top.

The portion forming the jaw 11 is of greater length than the jaw 12, and extends downwardly incurved slightly below the jaw 12, and then curved outwardly and upwardly as at 13, with its end inwardly and upwardly curved as at 14, within the bend 13.

The jaw 12 has a hooked end 15 to receive the eye 16, at the upper end of the member B, providing a pivotal connection between the two members A and B.

The member B is also made of a single piece of material, preferably non-corrosive wire, bent over and upon itself to form the eye 16, and the two spaced and parallel bars 17 and 18, which at a predetermined distance below the eye 16 are bent towards each other, their ends being twisted together, not only to retain the desired shape of the member B, but to provide a hand grip or handle 19. While I prefer to twist the lower ends 60 of the bars 17 and 18 together as shown in Figs. 1, 2 and 3, it will be readily understood that they may be secured together in any suitable manner, such for instance as shown in Fig. 4, by a knob 20.

After the members A and B have been assembled by placing the eye 16 of the member B over the hook 15 at the end of the jaw 12, the end of such hook is bent close to the jaw 12, so that there is no possibility of the 70 members becoming accidentally separated, and when so joined the lower curved portion of the member A will be in alignment with the opening between the side bars 17 and 18 of the member B.

This opening is of predetermined length so that when the member B is swung over towards the member A, the curved lower end of the member A contacts closely with the bottom of such opening, but the wire of the member A has sufficient yield to permit the passage of the curved portion of the member A into and through such opening in the member B with very slight pressure upon the handle 19 of the member B.

I prefer to slightly indent the wire of the member A at the point 21 to form a notch or recess into which the member B snaps when passed over the lower curved portion of the member A to check its forward movement.

The operation of the device is as follows:

The pin is attached to the line 22 by passing the jaw 12 over the line and then drawing the pin down until the line is firmly gripped between the jaws 11 and 12, there being sufficient yield in the wire for this purpose.

One edge of the garment or fabric 23 to be suspended is then passed over and around the curved portion of the member A as shown in Figs. 2 and 3. The member B is then swung forward towards the member A and over its lower curved portion whereby 105 110

the fabric 23 is clamped securely against both sides of the curved portion of the member A by the side bars 17 and 18 of the member B.

It will be seen that with the two members in such position it is impossible for the pin to become detached from the line, even though the jaws 11 and 12 loosen their grip upon the line in a very high wind.

While my invention is equally well adapted for use upon a single fixed clothes-line, I have illustrated it in Figs. 2 and 3 as applied to a pulley line in which case it will be seen that there is sufficient spread between the jaws 11 and 12 below the clamped line 22 for the return line 24 to be freely drawn therethrough.

My invention provides a very inexpensive, yet strong and durable clothes-pin, that may be easily attached to or released from a clothes line, but which cannot become accidentally detached therefrom; the clothes to be suspended by the pin do not come into contact with the line, and all danger of soiling the clothes from such cause, or by dropping to the ground is avoided.

I claim as my invention:

1. A clothes-pin comprising a body member provided at its upper end with jaws having a bight which yields to clamp a clothes-line, with a forwardly curved lower portion to receive the goods to be suspended, and a clamping member pivotally connected at one end to one of said jaws and provided with a vertical elongated opening adapted to pass over the said curved portion of the body

member and clamp the clothes against both sides thereof.

2. A clothes-pin comprising a body member, and a clamping member each formed from a single length of wire, the body member being bent over at a predetermined distance from its upper end to form a grip below which it is bent forwardly into approximately circular form, the clamping member being pivotally attached at one end to one jaw of said grip and provided with a vertical elongated opening adapted to pass over the circular bend of the body member when the clamping member is swung forward.

3. A wire clothes-pin comprising a body member formed from a single length of wire bent over at a predetermined distance from its top to form a grip, the extreme end of the bent over portion being bent into hook form, the wire extending below the grip and curved outwardly and upwardly with its end bent inwardly within said curvature, and a clamping member also made from a single length of wire bent over at its center to form an eye for pivotal connection with said hook on the body member, the bent over wire being crossed below said eye forming two oppositely spaced bars in vertical alignment extending downwardly a predetermined distance and then again crossed and the ends of the bars twisted together.

Signed by me this 14th day of March, 1927.

PAUL H. W. WENDT.
